UNITED STATES PATENT OFFICE.

HARRY S. ARAMIAN, OF NEW YORK, N. Y.

PEN NIB.

Application filed April 15, 1926. Serial No. 102,322.

This invention relates to graphic instruments and has particular reference to an improvement in pen nibs.

Primarily the invention comprehends an improved form of pen nib which functions to contain a large quantity of ink so as to eliminate the necessity of repeatedly dipping the same in the ink supply.

The invention furthermore contemplates an improved pen nib which is so constructed as to permit of its use at substantially any angle and in any rotated position with respect of its own axis.

The invention furthermore aims to provide a pen nib which is comparatively simple in its construction, inexpensive to manufacture, and which is highly efficient in its purpose.

With the above recited and other objects in view, reference is had to the following specification and accompanying drawings in which there is exhibited an example or embodiment of the invention which is in no way intended as a limitation upon the scope of the appended claims as it is to be clearly understood that variations and modifications which properly fall within the scope of said claims may be resorted to when found expedient.

30 In the drawings—

Figure 1 is a perspective view of a pen equipped with a nib constructed in accordance with the invention, illustrating the same in use;

35 Fig. 2 is a side view thereof;

Fig. 3 is a sectional view therethrough taken approximately on the line 3—3 of Fig. 2;

40 Fig. 4 is a perspective view of the nib blank.

Referring to the drawings by characters of reference, 10 designates a pen holder having an intermediate reduced portion 11 defining a shoulder 12 and a further reduced end portion 13 defining a shoulder 14. The pen nib 15 is of substantially cylindrical formation having an open upper end 16 of a diameter to snugly fit the reduced end portion 13 in abutting relation with the shoulder 14 and with its periphery flush with the periphery of the intermediate reduced portion 11. The opposite end of the nib body is provided with circumferentially spaced V-shaped cut-away portions 17 which define therebetween substantially V-shaped prongs 18 bent inwardly toward each other

so that the side edges 19 of the prongs are brought into contact and the apexes 20 of the prongs disposed in close relation to serve as a writing point, thereby in effect producing a conical closed end axially slotted. The material from which the same is formed is resilient so that pressure on the point of the closed end against a surface will effect a slight spread or opening of the prongs. The tubular or cylindrical body of the nib immediately adjacent the conical closed end is formed with a radial feeding opening 21 which is designed upon dipping of the nib within an ink supply, to permit a quantity of ink to feed into the conical closed end.

In order to prevent possible leakage of the ink from the nib in event of laying the pen down, a sleeve 22 is mounted on the reduced intermediate portion 11 of the pen holder for axial sliding movement, the same being limited in one direction by the engagement of one end with the shoulder 12; the opposite end is adapted to slide over the nib body to cover the opening 21 when the same is filled and ready for use. During the filling operation, the sleeve 22 is moved upwardly to uncover the opening as will be obvious. In writing, it is apparent that the nib may be rotated on its own axis and held at various inclinations so that when sufficient pressure is brought to bear, a separation of the prongs will permit the ink to flow for writing.

90 What is claimed is:

1. In a pen including a holder, a tubular nib having an open end fitted over the end of the holder and a conical lower end slotted upwardly from the apex to define resilient prongs, said nib having a radial filling opening through which ink is introduced to the interior thereof, means axially slidable relative to the nib for closing the filling opening, said closing means comprising a sleeve, and means on the holder for limiting the sliding movement of the sleeve in a direction to uncover the opening.

2. A pen including a holder having a reduced intermediate portion with respect to its upper end defining a shoulder and having a reduced lower end with respect to the intermediate portion defining a second shoulder, a nib having a tubular body open at its upper end and of a diameter to snugly fit the lower reduced portion of the holder with its periphery flush with

the intermediate reduced portion, said nib having a conical closed lower end slitted upwardly from its apex to define resilient prongs, the body of said nib having a filling opening adjacent its juncture with the conical lower end, a sleeve arranged for axial sliding movement on the holder and the tubular body portion of the nib to consti-

tute a closure for the filling opening, and an auxiliary means for connecting the nib with the holder, the upper end of the sleeve coacting with the upper shoulder to limit movement of the sleeve in a direction to uncover the filling opening.

HARRY S. ARAMIAN.
